ATTORNEY

UNITED STATES PATENT OFFICE.

ALLYN H. MARKERT AND GEORGE W. MARKERT, OF PHILADELPHIA, PENNSYLVANIA.

HOLDER.

Application filed February 10, 1921. Serial No. 443,854.

To all whom it may concern:

Be it known that ALLYN H. MARKERT and GEORGE W. MARKERT, citizens of the United States, residing at Philadelphia, in the 5 county of Philadelphia and State of Pennsylvania, have invented certain new and useful Improvements in Holders, of which the following is a specification.

The herein described device relates to 10 holders for milk-bottles, bread, newspapers, letters and articles of like nature, and to a device adapted to be removably attached to some portion of a dwelling as to make it adaptable for ready and instant use.

15 One of the objects of this invention is to provide a simple and practical device which can be easily and quickly attached to a pre-determined situation, and as easily and quickly removed when necessary, for the purpose 20 of acting as a receiver and holder of various articles. A further object is to provide a device as herein described which will be inexpensive to manufacture, reliable in use, convenient in operation, adapted to be 25 removably attached to prevent the depredations of animals as well as the spoiling of the contents by the unclean habits of animals, sanitary and attractive, of such simple construction that no parts can be broken 30 in use, and of such nature as to enable anyone to conveniently position and attach and use the same.

While the foregoing explains the general purpose and objects of the device, other objects and advantages will appear in the 35 specifications that follow, in which the novel features, construction and arrangement of the various parts will be brought out, described and claimed.

40 In the accompanying drawings, forming a part of this specification, and in which corresponding parts are denoted by like designating numerals is illustrated the preferred form of the embodiments of the invention 45 capable of carrying the same into practical operation, it being understood that the invention is not necessarily limited thereto, as various changes in shape, proportions, and general assemblage of the several parts may 50 be resorted to without departing from the principle of the invention or sacrificing any of its advantages, in which:—

Figure 1 is a plan view.

Figure 2 is a side view.

55 Figure 3 is a view in perspective, slightly enlarged, of the top of the device.

Figure 4 is a partial view in perspective showing one of the holding members.

To more fully describe the drawings, and to make clear the operation and the purpose 60 of the herein described device:—the numeral 1 shows a rear member having extending therefrom several members 2 for removably attaching the device. At the top and in front of the rear member and attached 65 thereto is a member 3 with the mouth sprung outwardly from the body thereof to receive and hold in place such articles as newspapers, magazines or like articles. Directly beneath said member and extending from 70 the rear member there is located the member 4 upon which is attached the securing element 5 adapted to receive and hold in position a small bottle, such as would be adapted to hold a pint of cream, or like substance; extending downwardly from the member 4 there is shown the member 6 at 75 the top of which is located the securing member 7 slightly sprung at the mouth adapted to receive a note or card upon which 80 is written the wants, or, more plainly, instructions or orders to the milkman, baker or grocer, the said securing member is also so constructed as to afford the letter carrier ample opportunity to place letters therein. 85 From the upright member 6 there extends the containing member 8 in which bread of a certain shape and size can be placed, the said bread containing member is held 90 against the upright member by the spring 90 situated upon a rod connected with the arms 11. When necessary to use the container it is opened outwardly and downwardly by grasping the member 9 and article placed within the container which is then 95 held securely by the above mentioned spring. Situated below the aforesaid upper container, there is shown another container 12 adapted for a like purpose as the upper, but which will also receive bread of a different 100 size and shape loaf, this containing member is held in position by the springs 14 maintained by the arms 14' and is operated by grasping the member 13 by which the said container member is pulled downwardly and 105 outwardly from the upright member until the article has been placed therein, and then permitted to rest against the upright member. At its lower end the upright member 6 is turned outwardly and upwardly forming the member 15 which is adapted and positioned so as to receive and hold the loops 110

or strings of a bag should it be that the user of the device did not desire the bread placed in the containing members as described above. Other uses will be manifest, such as 5 receiving bundles from the stores, parcel-post packages and such articles. On each side of the upright member 1 and the member 6 are located the members 16 of a circular shape adapted to receive and hold a 10 bottle of milk of the quart size, it is to be noted that both or either of the members can be occupied at the one time. On one of the circular members is located a spring actuated member 17 which is so constructed 15 as to grasp and hold in position a paper bag in which may be placed rolls or buns by the baker articles of a nature allied thereto.

What I claim as new and desire to secure by Letters-Patent, is:—

20 In a device for the purpose specified, in combination a single rear upright bent at its upper extremity to form securing means, outwardly and upwardly extending receiving means attached to the front of said upright, an arm situated below said receiving

means and extending outwardly from the upright, said arm having upwardly extending fingers situated thereon, the outer portion of said arm being bent and extended downwardly, parallel to the rear upright, the 30 downward extension of said arm having retaining means thereon and having below said retaining means a pair of outwardly extending arms supporting a spring actuated holder, a second pair of outwardly extending arms supporting a second spring actuated holder below said last named arms and holder and a pair of curved sections extending on either side of and connected with said rear upright and said downwardly extending arm, one of said curved sections having connected thereto a spring controlled clip. 40

In testimony whereof we affix our signatures in the presence of two witnesses.

ALLYN H. MARKERT.
GEORGE W. MARKERT.
